CLAIM

The ornamental design for a fireproof safe box, as shown and described.

DESCRIPTION

FIG. 1 is a first perspective view of a fireproof safe box showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is another perspective view thereof, shown in an open position.

The broken lines shown in the drawings depict portions of the fireproof safe box that form no part of the claimed design.
